Primary Examiner — Rhea Shields(74) *Attorney, Agent, or Firm* — FOLEY & LARDNER LLP(57) **CLAIM**

The ornamental design for an outlet as shown and described.

DESCRIPTION

FIG. 1 is a front perspective view from above of the claimed outlet according to the claimed design;

FIG. 2 is a front view of the claimed design of FIG. 1;

FIG. 3 is a rear view of the claimed design of FIG. 1;

FIG. 4 is a left side view of the claimed design of FIG. 1;

FIG. 5 is a right side view of the claimed design of FIG. 1;

FIG. 6 is a top view of the claimed design of FIG. 1; and,

FIG. 7 is a bottom view of the claimed design of FIG. 1.

Any portion of the article depicted in broken lines forms no part of the claimed design. Broken lines formed by equal length dashes show unclaimed portions of the design. Broken lines formed of unequal length dashes (i.e., dash-dot) show boundaries between claimed and unclaimed portions of the design. Broken lines having a jagged element show that no particular length of that portion of the article is claimed, such lines and any portion of the article between such lines form no part of the claimed design. Oblique lines can also be used to illustrate a reflective or glossy surface.
